UNITED STATES PATENT OFFICE.

BENNET HOTCHKISS, OF NEW HAVEN, CONNECTICUT.

IMPROVEMENT IN DROP-PRESSES.

Specification forming part o. Letters Paten. No. 37,692, dated February 17, 1863.

To all whom it may concern:

Be it known that I, BENNET HOTCHKISS, of the city and county of New Haven, and State of Connecticut, have invented new and useful Improvements in Drop-Presses; and I do hereby declare the following to be a full, clear, and exact description of the construction and operation of the same, reference being had to the accompanying drawings, making a part of this specification, in which—

Figure 1 is a front view. Fig. 2 is a side view; Fig. 3, detached parts enlarged.

Same letters refer to like parts.

The nature of my invention consists in a mechanism whereby I am enabled to instantly release my drop at any point in its ascent desired by the operator, for the purpose of giving heavier or lighter blows, as the work may require.

To enable others skilled in the art to construct and operate my invention, I will proceed to describe my manner of so doing.

A is the anvil, also supports the drop B and its operative mechanism.

The upper part or frame C is constructed so as to form guides c c to receive and guide the drop B.

D is a strap, or its equivalent attached its lower end to the drop B, the other passes up and between the pulleys E and F. The pulley E is fixed to a shaft, a, driven by another pulley G, also fixed to the same shaft, and to which I apply the power to operate the drop. b is a cog-wheel, fixed to the same shaft a, and engages into another cog-wheel, d, fixed to the pulley F, which is loose upon an eccentric-shaft, H, the eccentric bearings e of which rest in boxes I. To this eccentric-shaft H (see Fig. 3) I attach and fix a lever, L, for the purpose of turning it on its eccentric bearings to force the loose pulley F toward the fixed pulley E and against the strap D with sufficient force to hold the strap firmly between the two pulleys, which, when so held, will, by the revolutions of the two pulleys in the direction denoted by arrows, draw the strap D and the drop B, to which it is attached, upward, and when the eccentric-shaft is returned by raising the lever L, as shown in red, Fig. 3, will release the pressure upon the strap, when the drop will fall.

f is a spring-latch to catch and hold the lever L down, as shown in Fig. 3 in black,

when the pulley F shall have been pressed with sufficient force against the strap to raise the drop, as before described.

M is a rod, its upper end attached to the lever L by a slot, g, and on which are fixed adjustable stops h and i, for the purpose of operating the eccentric-shaft to force the pulley F to and from the pulley E.

N is a projection from the drop, which in the ascent of the drop strikes the stop h and raises the rod M, (see Fig. 1 in red,) which by a projection, n, (see Fig. 3,) formed on the rod for the purpose, presses back the spring-latch f, as shown in red, Fig. 3, and releases the lever L, which raises in consequence of the overbalancing of its longer arm, O, or by a weight or spring thereto attached. The slot g in the upper end of the rod M is to allow time to operate the latch f to release the lever L more suddenly than the ascending drop otherwise could do, and therefore causing an instantaneous release of the pressure upon the strap, when the drop will fall from its full height without resistance, whereas were the pressure gradually released, the drop would begin its descent before a full release had taken place, and a consequent resistance would attend the drop during a portion of its descent. In the descent of the drop the projection N strikes the stop i and draws down the rod M, and through its connection the lever L into the latch f, as shown in black, Fig. 3, when the strap is again grasped between the two pulleys as before.

P is a trip hung to the adjustable block R. o is a spring to hold the trip up, as shown in black, Fig. 1. In the ascent of the drop the projection N strikes the inner end of the trip P, and raises and passes it, when, if the trip is allowed, it will spring back under the projection N and catch the drop immediately after its release, (see Fig. 1 in blue,) where it will remain until the trip is drawn down, as shown in blue, Fig. 1, when the drop will fall, and, striking the stop i, will again be raised, as before described, and so continue to be raised and fall until the trip is allowed to spring back to catch it and hold it up. When it is desired to make the blows heavier, the stop h must be raised and reset on the rod M by the set-screw r at a point to give the desired length of stroke, or, if for a lighter blow, must be lowered accordingly. The slide to

which is hung the trip P is also adjustable on the frame C, and fixed in place by a set-screw, s, and should be raised or lowered, so as always to be in about the same relative position to the stop h. By this arrangement I am enabled to obtain any required length of stroke to the extreme height of the guides, and to strike very rapid blows in consequence of the impossibility of the pulleys catching the strap until the drop has fallen so far as to strike the stop i to close the pulleys upon the strap, while drops driven by cranks are confined to a fixed length of stroke and a limited velocity, as a too rapid revolution of the crank will catch the drop before it has completed its descent. The stop i is adjustable, and may be raised or lowered, as the work may require. When at rest, the drop is in the position as shown in blue, Fig. 1, and when to be used, place the work upon the anvil A, set the foot in the stirrup T and draw the trip P away to allow the drop to fall, which, as before shown, will be immediately raised, and so continue to fall and be raised till the trip is released and springs back to catch it in its descent.

I illustrate my invention as having the power applied to the shaft having a fixed center, but it may be applied to either or both with the same result and without departure from the principles herein set forth. Therefore

I do not confine myself to the precise construction of the several parts, reserving to myself the right to modify so long as I do not depart from the general principles herein contained.

Having fully described my invention, what I claim therein as new and useful is—

1. The eccentric pulley F, in combination with the pulley E, when the same operate in the manner and for the purpose, substantially as herein set forth.

2. The eccentric pulley F and drop A, when the same are combined, substantially for the purpose as herein specified.

3. The lever L and latch f, when the same are combined in the manner described, with the eccentric pulley F, for the purpose specified.

4. The combination of the lever L and latch f with a drop, substantially as herein described.

5. The rod M, with its adjustable stops h and i, in combination with the lever L and latch f, substantially in the manner and for the purpose herein set forth.

6. The adjustable trip, in combination with a drop, substantially as and for the purpose specified.
